UNITED STATES PATENT OFFICE

GEORGE R. WOLF, OF ARLINGTON HEIGHTS, ILLINOIS

PROCESS OF SETTLING COAL DUST

Application filed May 20, 1927. Serial No. 192,820.

My invention relates to a method of settling coal dust and the like.

In the past, householders and other consumers of coal have experienced considerable hardship and trouble with coal dust. Especially is this true in the case of the soft or dust coal, commonly called "Pocahontas" coal. Even the slightest agitation of the coal in the bin will result in a cloud of dust, which is either scattered or carried throughout the house.

Now, obviously, each time a truck of coal is delivered to the consumer, the dust created by the discharge of the coal into the bin will be scattered throughout the basement of the house and even into the upper floors thereof. This dust not only entails considerable additional work on the part of the householder, but also necessitates the closing of all the doors leading from the upper floors to the basement or floor in which the coal bin is located. Moreover, the coal dust thrown into the air is breathed into the lungs of the people occupying the house, which is not only detrimental to the health of these people, but is very uncomfortable and unpleasant to them.

I have found that no matter how well the walls of the bin are constructed, still the dust will escape from the bin either around or under the door leading to the bin, or through any other available crevices in the wall. Also, it is to be noted that this coal dust has value as fuel and that if it could be economically saved, the given heat value of each unit or ton of coal would be augmented.

The object of the present invention is to provide an economical method of and apparatus for settling the coal dust in the bin and for preventing it from escaping therefrom.

Another object of the present invention is to provide a relatively simple and inexpensive portable device adapted to be used in conjunction with the delivery of coal into a bin to settle the coal dust in the bin. This device is of such a construction that it may be carried about with facility on the conventional coal truck. It may also be readily installed in the coal bin preparatory to the discharge of the coal from the truck into the bin. In fact, I propose utilizing

my invention in connection with a service to be rendered to coal consumers. For this service a nominal charge can be made of, say twenty-five cents a ton. It will be evident that many housewives would much rather pay the twenty-five cents a ton extra than to have to contend with the coal dust which settles throughout the house.

Also, I desire it understood that although my invention is particularly useful in connection with the delivering of coal, it is not to be limited in this single application for, obviously, it could be used to settle other forms of dust without deviating from the features of the invention. Therefore, the invention should only be limited by the scope and spirit of the appended claims.

Other objects and advantages of my invention will more fully appear from the following detailed description taken in connection with the accompanying drawings, which illustrate several embodiments thereof, and in which:

Figure 1 is a fragmentary view, partly in section, illustrating the manner in which my novel device is connected to a coal bin;

Figure 2 is a plan view, partly in section, with the construction shown in Figure 1;

Figure 3 is a fragmentary sectional view illustrating a modified application of my invention;

Figure 4 is a fragmentary sectional plan view of a modification of the invention;

Figure 5 is a fragmentary plan view, partly in section, of a modified application of my invention, and

Figure 6 is a fragmentary sectional plan view illustrating another modification of the invention.

It is thought that my novel process will be fully understood from the following detailed description of an apparatus capable of performing it.

In the drawings:

Like reference numerals designate similar parts throughout the several views. The reference numeral 10 designates generally a coal bin defined on one side by a wooden board wall 11 and on the other three sides by solid walls 12, 13 and 14. The wall 12 is pro-

vided with an opening 13 adapted to be closed by a closure or door 14 (Figure 2). The wall 14 is provided at one end with a slanting portion 15 having an opening 16 through which coal may be discharged into the coal bin 10. This opening 16 may be closed by any suitable means such as, for example, a closure member 17.

The coal pile is designated generally by 10 the reference character 20. This coal is delivered into the bin through the opening 16 in a manner well known to coal consumers. Obviously, with each delivery of coal into the bin, considerable coal dust will be set free 15 into the atmosphere. If it were not for my present invention, the coal dust would seep through the cracks between the boards composing wall 11 and through the openings about the door 14 into the room or rooms adjoining the bin 10. Since the coal bin is usually located in the basement of the house, I have illustrated my invention as applied to 20 such a bin in the basement of a building. The space or room on the exterior of the bin 10 has positioned therein a furnace 21 of any 25 conventional construction. As will be more fully described hereinafter, my portable construction may be coupled to either the furnace 21 or the chimney 22 associated with furnace 21.

It will be evident that the coal dust leaving the bin 10 will not only settle in the basement, but will be scattered throughout the other floors of the building. This dust is 30 difficult to remove from the furniture and, as previously pointed out, is more or less detrimental to the health of the persons in the house. Therefore, it is highly desirable to eliminate the same, if for no other reason than to protect the health of the housewife.

In order to prevent the dust from leaving the bin, I provide a portable unit 25 comprising a fan or blower 26, a motor 27 for actuating the same and a common support 28 for both the fan and motor. The fan or blower 26 may be operatively connected to the motor 27 by any conventional mechanism. The fan 26 has a discharge opening 29 and an inlet 30. The discharge opening 29 of fan 26 is connected to a flexible pipeline 31. This pipeline may extend through a suitable opening in the wall 12 designated by numeral 32 and may have its end on the exterior side of the coal bin connected directly to the chimney 22 at 33, or if it is so desired, it may be connected to the lower part or grate of the furnace and thus indirectly discharge into the chimney. The unit 25 may be supported upon the wall 12 by means 50 of a bracket 35. Of course, it is to be understood that any other suitable means may be used to support the motor unit without deviating from the features of my invention. The motor 27 is preferably provided with 55 flexible conductors 36 having their ends ter-

minating in a conventional plug 37 adapted to be inserted in any standard electrical socket 38.

In operation, the blower or fan 26 will function to suck air from the interior of the bin. This air will be discharged through the pipeline 31 into the chimney 22. Obviously, by sucking air from the coal bin 10, additional air will be forced into the bin through the cracks in the board wall 11 and in the openings around door 14. This inrushing air will force any dust in the interior of the bin downwardly onto the floor thereof.

In actual practice, the unit 25 is set into operation so that it functions contemporaneously with the delivery of coal into the bin. It will be evident that the dust in the coal will be forced downwardly due to the inrush of air created by the suction of the fan. As a result of this inrush of air practically all of the coal dust will be forced downwardly with the coal onto the floor of the bin, and hence no appreciable amount of dust will be free to leave the bin.

The unit 25 may be made portable so that it may be installed with facility in any coal bin prior to the delivery of coal thereto. In fact, the coal company making the delivery might even go so far as to provide such portable units so as to enable the performance of an additional service to their customers. The ordinary housewife would gladly pay an additional twenty-five cents a ton for this service rather than to go through the hardships and troubles usually experienced by the spreading of the coal dust throughout the house. The portable unit may be readily installed in the bin by the coal trucker prior to the delivery of coal and may be removed with facility when the delivery is accomplished.

In Figure 3 I have illustrated a modified manner of mounting the unit 25. In this form of the invention, the unit 25 is attached to the wall 14 and has its pipeline 31 extending out of the bin through the opening 16. The external end of the line 31 may terminate in a bag 39. This form of the invention may be used where there is no chimney in proximity to the coal bin.

If it is so desired, the unit 25, as shown in Figure 4, may be mounted in the space 50 on the exterior of the bin 10. The unit 25 in this event may be suitably fastened to the wall 12 with the intake opening 30 of the blower 26 disposed in alignment with an opening 51 in wall 12. The motor 27 may be suitably connected to an electrical circuit by means of the flexible conductors 36 and the plug 37 insertable in a socket 38'. The discharge pipeline 31 of the unit 25 is connected to a dust collecting device or bag 53. This bag has a discharge pipe 54 disposed in communication with the atmosphere in space 50.

Now, obviously, the unit 25 shown in Fig-

ure 4 will function to suck air from the bin 10. This air will pass through the blower 26 and will be discharged into the dust collector 53. The air, after passing through the collector 53, is projected into the space 50. It will be evident that a subnormal pressure will be created in the bin 10, and an abnormal pressure will be created in the space 50. This means that the air will rush in from the space 50 into the bin 10 to take the place of the displaced air in the bin, and in so doing will force the particles of dust to the floor of the bin. The advantage of this construction is that the circulation of air between the space 50 and the bin 10 is increased due to the abnormal pressure in space 50.

The modified use of the invention shown in Figure 5 is substantially like that shown in Figure 4, with the exception that the pipeline 31 of unit 25 is connected directly to the grate of the furnace 21 and discharges into the chimney through the furnace. The blower 26 of unit 25 will function to suck air from the bin 10 and to deliver the displaced air to the furnace 21 in space 50. This results in a subnormal pressure being created in bin 10 and causes an inrush of air into the bin.

Instead of sucking air from the bin 10, it is also within the contemplation of my invention to force air into the bin for the purpose of causing the dust to settle therein. This modified use of the invention is shown in Figure 6. A unit 25 is disposed on the outside of the room 50 and has its pipeline 31 extending through a window 55 disposed in communication with space 50. The intake opening 30 of blower 26 is disposed in communication with the atmosphere and is adapted to suck air into the blower 26, which forces the air into pipeline 31. The air under pressure in pipeline 31 is discharged into the space 50, as shown in Figure 6 by the arrows. This discharged air penetrates the cracks and openings about door 14 and enters the bin 10. Obviously, the air under pressure entering bin 10 will force the coal dust within the bin to settle on the floor thereof, thus preventing the spreading of the coal dust. The motor 27 of the unit 25 shown in Figure 6 may be connected to any suitable source of electrical power.

Now, I desire it understood that although I have illustrated and described in detail the preferred forms of my invention, the invention is not to be thus limited, but only in so far as defined by the scope and spirit of the appended claims.

I claim as my invention:

1. The process of settling coal dust and the like in a bin which consists in discharging the dust into the bin, contemporaneously sucking air from said bin and causing the incoming dust to drop to the bottom of the bin by the

effect of the air rushing into the bin to take the place of the displaced air.

2. The process of settling coal dust and the like in a coal bin with non-airtight walls while coal is being delivered therein which consists in creating an abnormal air movement condition in the bin contemporaneously with the delivery of coal into the bin and utilizing said air movement condition to cause conflicting air current to seep into the bin through openings and the like in the walls of the bin whereby eddying air currents are set up in the bin causing floating coal particles to settle within the bin.

3. The process of settling coal dust and the like in a coal bin having non-airtight walls which consists in creating an abnormal air condition in the bin contemporaneously with the delivery of coal into the bin and utilizing said abnormal air condition to cause the air about the walls of the bin to be drawn or forced in a direction toward the interior of the bin through openings and the like in the walls thereof.

In testimony whereof I have hereunto subscribed my name.

GEORGE R. WOLF.
